MOTOR FOR PUMPING MECHANISMS

Wade H. Wineman, Michigan City, Ind., assignor to Sullivan Machinery Company, a corporation of Massachusetts

Application September 29, 1934, Serial No. 746,170

28 Claims. (Cl. 121—126)

This invention relates to pumping mechanisms, and more especially to expansible chamber motors which, while suitable for a wide variety of purposes, find particular utility in the oil well pumping field.

There is in certain oil fields a substantial quantity of oil available, but not under sufficient pressure to cause the same to rise to the surface. It is accordingly necessary to provide for the pumping of this oil; and a very satisfactory system has been devised which includes a number of pumping units arranged in reasonable adjacency to a central air compressor plant which supplies operating fluid under pressure to the pumping units and recompresses the fluid after it has been used in the pumping units. Ordinarily the unit at each well in this system includes a pump head in the form of a single-acting expansible-chamber motor, the latter being connected with a piston or other suitable type of pump in the oil well. To provide for economical operation, pre-heating of the air just before its admission to the pumping motors is practiced at the wells; and it is common to maintain a substantial back pressure on the motor cylinders for the purpose of precluding unduly rapid dropping of the pump rod line; and accordingly the air that has been used in the pump cylinders is returned to the central compressor plant under a substantial pressure. Suitable make-up means is provided for supplying additional air to the system as necessary. As it is not practicable to have an operator at each well, it is quite important that the pumping motor shall be very reliable and simple in construction and positive in action, and it is also desirable, for testing and other purposes, to provide a motor which is adapted to operate either on the rectangular cycle or with expansion and compression, at the option of the system operator.

One object of the present invention is to provide an improved pumping motor, particularly adapted for the use described. Another object of my invention is to provide an improved single-acting expansible chamber motor of general application. A further object of my invention is to provide an improved single-acting pumping motor having an improved fluid-actuated valve gear. Yet another object of my invention is to provide an improved and simple fluid-actuated valve gear of general application. Other objects and advantages of my invention will hereinafter more fully appear.

In the accompanying drawings, in which, for purposes of illustration, there are shown one em-

bodiment and a modification which my invention may assume in practice,—

Fig. 1 is a side elevation, with parts broken away, showing a portion of the pumping mechanism arranged at a well which is to be pumped and incorporating a pumping motor constructed in accordance with the illustrative embodiment above mentioned;

Fig. 2 is a view partially in side elevation and partially in central vertical section (the latter portion showing the valve mechanisms) through the motor of Fig. 1;

Figs. 3 to 6, inclusive, show relative positions of parts at different points in the cycle of the motor;

Figs. 7 and 8 are detail sectional views respectively of lower and upper cycle-changing devices, Fig. 7 being taken on the plane corresponding to the section line 7—7 of Fig. 1, and Fig. 8 on a right angle plane, and

Fig. 9 is a view showing a modification.

Referring first to Fig. 1, it will be observed that upon a platform 1 there is mounted a suitable frame 2 of structural steel or the like and having a top member 3. The latter pivotally supports at 4 the upper head 5 of a pumping motor 6 whose cylinder member 7 is suitably positioned with respect to the upper head 5. The motor 6 also has a lower head 8 which incorporates, as will later be described, supply and exhaust passages, and houses the admission and exhaust valves. The heads 5 and 8 and the cylinder 7 may be held assembled by threading or by suitable side rods extending between the heads and clamping the cylinder between them. As any suitable form of construction adapted to hold the parts assembled may be used, details have not been illustrated.

Air is supplied through a suitable supply line 10 from a central compressor plant (not shown) and enters a preheater 11 which may be fired by gas or oil as desired, and after preheating, enters the pipe 12 and flows through the latter, under the control of a stop valve 13 and an automatic control valve 14, the latter operative to close off supply if the motor loses its load, into the lower cylinder head 8. A suitable vent valve 15 is arranged between the stop valve 13 and the automatic control valve 14. The fluid, after working in the motor 6, is discharged to a line 16 controlled by a shut-off valve 17, and is adapted to be returned to the intake side of the compressor of the central compressor plant, which has not been shown. The motor 6 has a piston 20 provided with a piston rod 21 which is connected,

through a suitable adjustable connecting device 22, with a pump line 23 leading down into the well to a reciprocatory pump (not shown) near the bottom of the well. Oil raised by the pump 5 is dischargeable through the connection 24, and gas from the well is discharged from a pump head 25 through a suitable line 26.

Now referring more in detail to the motor, it will be observed that the lower head 8 has an initial chamber 30 to which the connection 12 leads. The chamber 30 is separated by a partition 31 from a space 32, which communicates through a port 33 with the lower end of the cylinder bore 34. The partition 31 is ported at 35 and the port is surrounded by a valve seat 36. The port is adapted to be controlled by an admission valve 37 which may be rigidly or pivotally connected, as desired, with a piston 38 which is formed integral with a larger piston 39. The piston 39 is reciprocable in a cylinder 40 suitably mounted upon the upper side of the lower cylinder head 8, and is closed by a head 41 and is vented at its lower end, as at 42. This vent may open directly to the atmosphere or have fluid conducted away therefrom to any place 25 where it is desired to discharge the fluid which may leak past the pistons. The piston 38 is of a cross-sectional area substantially the same as that of port 35, so that, when the valve is seated, the net effect of the pressure in the chamber 30 30 upon the valve is a tendency to maintain the valve 36 seated. This is due, of course, to the fact that the valve is larger than the piston 38. The valve, of course, is subject to the pressure within the cylinder upon its lower end; and the upper end 35 of the piston 39 is subjected to pressure variations in a manner which will now be described, to control valve movements.

A connection 44 enters the cylinder 40 through the head 41, and at the upper end of the connection 44 the latter enters a T 45 from which branches 46 and 47 lead off. The connection 46 is controlled by a check valve 48 suitably spring-loaded, as at 49, and controlling and adapted to open to permit flow of the fluid toward the connection 44 but precluding flow in the opposite direction. A connection 50 leads from the upper end of the check valve to a point of communication 51 with the motor cylinder 7, though communication with the motor cylinder at a higher point 52 is possible under the control of a manually adjustable control valve 53. The connection 47 is also controlled by a check valve 54, this check valve opening to permit discharge of fluid from the connection 44 but precluding entry of fluid past the check valve 54 to the passage 44. The check valve 54 is also spring-loaded, as at 55, and is connected between the connection 47 and a connection 56 which communicates with the cylinder bore at 57.

The exhaust valve 59 cooperates with a seat 60 surrounding a port 61 formed in a partition 62 which separates the exhaust port 63 from the chamber 64 connected with the pipe 16 which leads back to the compressor intake. The exhaust valve is provided with a loosely fitting guiding stem 66, upon which a spring 67 acts normally to maintain the exhaust valve seated whenever the position of its control piston mechanism, shortly to be described, permits. The exhaust valve is adapted to be moved to open position by a piston mechanism 68 mounted in the cylinder 69 which has an upper head 70. The piston 68 comprises a lower portion 71 of a cross-sectional area substantially the same as the cross-sectional area of the 75 exhaust port 61, the exhaust valve 59 also has an

upwardly-extending stem 66^a seated within a bore 66^b in the piston mechanism 68, as in the structure of my Patent No. 2,004,146, this construction enabling piston mechanism 68 to open valve 59 at appropriate times and also enabling pressure in line 16 to pass valve 59 and open valve 37, when the motor is to be first put in operation. The piston mechanism 68 also comprises a larger head 73, reciprocable in a bore 74 which is vented at 75 at its lower end. The space above the piston 10 73 has communication with a fluid supply and exhaust connection 76 which, through a T 77, communicates with a pair of passage-forming members 78 and 79. Passage 78 is controlled by a spring-loaded check-valve device 80 which permits flow toward the exhaust valve controlling piston 73 but precludes reverse flow. The check valve 80 is connected by a pipe 81 for communication with the bore of the motor cylinder at the point 52. The pipe 79 is connected by a check-valve device 83, opening away from the piston 73, with a pipe 84, which normally is adapted to communicate with the bore of the motor cylinder at 85 but which may be connected, under the control of a suitable valve mechanism 86, with the bore of the cylinder at 57. The connection 57 is uncovered by the top of the piston 20 shortly before the latter reaches the bottom of its inactive strokes. The connection 85 is uncovered by the top of the piston somewhat earlier in the 30 downward stroke. The connection point 51 is uncovered by the bottom of the piston on its upward strokes at a point suitable for cut-off to occur if operation with expansion is desired, and the point 52 is uncovered by the bottom of the piston 20 as 35 the latter reaches substantially the top position desired for its working stroke. Plugs 87 are provided to permit changes in location of the connection-points 51 and 85 if desired. The top of the cylinder has a vent of suitable size at 88. 40.

The mode of operation of the apparatus as heretofore described will now be readily understood. Motive fluid entering the chamber 30 through the supply line 12 is admitted, in the position of the parts shown in Fig. 2, past the admission valve 37 and through the port 35 into the space which is connected by the port 33 with the bottom of the motor cylinder bore 34. This working fluid at line pressure, say 250 or 300 pounds per square inch, acts beneath the piston 20 and serves to move the latter upwardly, the exhaust valve 59 being closed. As the piston 20 moves upward in the bore 34, it first uncovers with its lower edge the connection point 51, but irrespective of the position of the valve 86 no fluid can be admitted either above the piston 39 or above the piston 73 because the check valves 54 and 83 prevent flow through the connections 56 and 84. The piston continues its upward pass and then uncovers the connection point 85 which, if the valve 86 is in lower position, would constitute the first point for admission to the connection 84. However, no fluid would flow from the cylinder bore past the check-valve device 83 to act upon the piston 73. The piston 20 continues to rise and uncovers the connection point 51. Now, if the valve mechanism 53 is arranged to effect operation with expansion, the fluid admitted through the connection 51 will pass into the connection 50 and unseat the check valve 48 and pass to the upper side of the piston 39, which it will promptly depress and thereby close the admission valve 37. The motor piston 20 will, however, continue to rise under the expansion of the fluid within the cylinder bore 34 until 75

its lower edge uncovers the connection point 52, and then fluid will pass through the connection 81, unseat the check valve 80, and enter the cylinder 74 where it will act upon the piston 73 and thereby open the exhaust valve; and release will then occur. Thereupon the weight of the rod line and the connected parts will cause downward movement of the piston 20 at an appropriate rate, and the fluid in the motor cylinder will 10 pass, at the back pressure maintained in the discharge line 16, back to the compressor intake. When the upper surface of the piston 20 uncovers the connection-point 52 there will be no escape of the fluid above the piston 73 because the check valve 80 will prevent flow in that direction through the connection 81. Likewise, when the upper surface of the piston uncovers the connection point 51, no escape of the fluid above the piston 39 will take place because of the 20 presence of the check valve 48. When, however, the upper surface of the piston passes below the connection-point 85, the pressure above the piston 73 will be released provided the valve mechanism 86 is arranged to effect operation with compression, and check valve 83 will permit flow from the space above the piston 73 through connection 76, T 77, connection 79 and connection 84 to the connection point 85 and thus to atmosphere through 88. The exhaust valve 59 will then 25 be closed by reason of the fact that there will be an unbalanced area acting upwardly on piston 71 to lift the latter, such area equal to the cross sectional area of piston 71, and the pressure of the spring 67 acting upwardly together with the rush of exhausting fluid will close the exhaust valve when piston 71 moves up. The piston 20, however, will continue to move downwardly until the port 57 is uncovered and then the pressure above the piston 39 will be vented 30 through the connection 44, T 45, connection 47, unseated check valve 54, connection 56, and connection point 57 to the vented space above the piston 20, which space is in communication with the atmosphere as previously described. The admission valve 37 will then be opened by the 35 uncounterbalanced pressure within the lower end of the motor cylinder acting upon the lower end of the seated valve, and admission will then occur and the cycle will be repeated.

50 A rectangular cycle can be effected by the suitable positioning of the mechanisms 53 and 86, but it will be noted that, as shown in Fig. 9, these mechanisms may be omitted and connections 50 and 81 joined directly to each other and connected through a common passage to the cylinder bore, and connections 56 and 84 joined together and, through a common passage, connected to the cylinder bore. The admission valve will always close before the exhaust valve opens and the exhaust valve close before the admission valve opens, due to the pressure differentials described.

55 This may be explained as follows: Even though simultaneous admission to pistons 39 and 73 occurs, 39 is opposed only by an area equal to the cross sectional area of 38, while 73 is opposed by a larger area, subjected to the same pressure as 38, plus spring 61; and even when ventings of 39 and 73 concur, opening of 37 will be opposed by the live pressure on the unbalanced annular area at the periphery of 37, while closing of 59 will be aided by spring 61.

60 It will be noted that I have provided a very positive, simple and efficient valve gear and motor, one well-adapted to completely automatic

operation with a minimum of attention, and that there is a maximum assurance of reliable operation due to the lack of any parts likely to become broken or deranged. If desired the check valves may be positioned so that gravity will act 5 in valve-closing direction, and thus provide even greater assurance of freedom from trouble.

65 While there are in this application specifically described one form and a modification which the invention may assume in practice, it will be understood that this form and the modification are shown for purposes of illustration and that the invention may be further modified and embodied in various other forms without departing from its spirit or the scope of the appended claims. 10 15

What I claim as new and desire to secure by Letters Patent is:

1. In a motor, in combination, a cylinder, a piston reciprocable therein, and valve mechanism for said motor including a valve and controlling means therefor having a pressure area acting to move said valve, and means for supplying pressure to said area and venting pressure therefrom including conduits respectively having their extremities remote from said area opening into communication with the cylinder bore at points widely spaced longitudinally of the latter and at opposite sides of normal mid-stroke position but both covered and also uncovered by each end of the piston during each complete cycle of piston movement. 20 25 30

2. In a motor, in combination, a cylinder, a piston reciprocable therein, and valve mechanism for said motor including an admission valve and controlling means therefor having a pressure area acting to move said valve to closed position, and means for supplying pressure to said area and venting pressure therefrom including conduits respectively having their extremities remote from said area opening into communication with the cylinder bore at points widely spaced longitudinally of the latter and at opposite sides of normal mid-stroke position but both covered and also uncovered by each end of the piston during each complete cycle of piston movement. 35 40 45

3. In a motor, in combination, a cylinder, a piston reciprocable therein, and valve mechanism for said motor including an exhaust valve and controlling means therefor having a pressure area acting to move said valve to open position, and means for supplying pressure to said area and venting pressure therefrom including conduits respectively having their extremities remote from said area opening into communication with the cylinder bore at points widely spaced longitudinally of the latter and at opposite sides of normal mid-stroke position but both covered and also uncovered by each end of the piston during each complete cycle of piston movement. 50 55 60

4. In a motor, in combination, a cylinder, a piston reciprocable therein, and valve mechanism for said motor including a valve and controlling means therefor having a pressure area acting to move said valve, and means for supplying pressure to said area and venting pressure therefrom respectively having check-valve-controlled communication with the cylinder bore at points widely spaced longitudinally of the latter whereby flow therethrough is unidirectional irrespective of the position of the piston in the cylinder. 65 70

5. In a motor, in combination, a cylinder, a piston reciprocable therein, and valve mechanism for said motor including an admission valve and controlling means therefor having a pressure area acting to move said valve to closed position, and means for supplying pressure to said area and 75

venting pressure therefrom respectively having check-valve-controlled communication with the cylinder bore at points widely spaced longitudinally of the latter whereby flow therethrough is unidirectional irrespective of the position of the piston in the cylinder.

5. In a motor, in combination, a cylinder, a piston reciprocable therein, and valve mechanism for said motor including an exhaust valve and controlling means therefor having a pressure area acting to move said valve to open position, and means for supplying pressure to said area and venting pressure therefrom respectively having check-valve-controlled communication with the cylinder bore at points widely spaced longitudinally of the latter whereby flow therethrough is unidirectional irrespective of the position of the piston in the cylinder.

6. In a motor, in combination, a cylinder, a piston reciprocable therein, and valve mechanism for said motor including a valve and controlling means therefor having a pressure area acting to move said valve, and means for supplying pressure to said area and venting pressure therefrom respectively having check-valve-controlled communication with the cylinder bore at points widely spaced longitudinally of the latter, the check-valve-controlled communication with the cylinder point nearer said valve precluding flow from the cylinder towards said area and the check-valve-controlled communication with the cylinder bore at a point more remote than the first-mentioned point from said valve precluding flow from said area towards the cylinder bore.

7. In a motor, in combination, a cylinder, a piston reciprocable therein, and valve mechanism for said motor including an admission valve and controlling means therefor having a pressure area acting to move said valve to closed position, and means for supplying pressure to said area and venting pressure therefrom respectively having check-valve-controlled communication with the cylinder bore at points widely spaced longitudinally of the latter, the check-valve-controlled communication with the cylinder point nearer said valve precluding flow from the cylinder towards said area and the check-valve-controlled communication with the cylinder bore at a point more remote than the first-mentioned point from said valve precluding flow from said area towards the cylinder bore.

8. In a motor, in combination, a cylinder, a piston reciprocable therein, and valve mechanism for said motor including an exhaust valve and controlling means therefor having a pressure area acting to move said valve to open position, and means for supplying pressure to said area and venting pressure therefrom respectively having check-valve-controlled communication with the cylinder bore at points widely spaced longitudinally of the latter, the check-valve-controlled communication with the cylinder point nearer said valve precluding flow from the cylinder towards said area and the check-valve-controlled communication with the cylinder bore at a point more remote than the first-mentioned point from said valve precluding flow from said area towards the cylinder bore.

9. In a motor, in combination, a cylinder, a piston reciprocable therein, means for continuously venting one end of said cylinder, and means for controlling admission and exhaust with respect to the opposite end of said cylinder including an exclusively admission valve opened

75 by the pressure in said last mentioned cylinder

end following exhaust valve closure and a structurally-independent, exclusively exhaust valve whose closing is controlled by motor back pressure and means for effecting opposite movements of said valves by working pressure from the working end of the cylinder each having but a single supply connection operative to transmit valve-throwing pressure to effect valve movement, and controlled by piston movement.

10. In a motor, in combination, a cylinder, a piston reciprocable therein, means for continuously venting one end of said cylinder, and means for controlling admission and exhaust with respect to the opposite end of said cylinder including an admission valve opened by the pressure in said last mentioned cylinder end following exhaust valve closure and an exhaust valve whose closing is controlled by motor back pressure and means for effecting opposite movements of said valves by working pressure from the cylinder including a check-valve-controlled supply connection for each valve, controlled by piston movement and precluding flow towards said cylinder through said connection irrespective of piston position in the cylinder.

11. In a motor, in combination, a cylinder, a piston reciprocable therein, means for continuously venting one end of said cylinder, and means for controlling admission and exhaust with respect to the opposite end of said cylinder including an admission valve opened by the pressure in said last mentioned cylinder end following exhaust valve closure and an exhaust valve whose closing is controlled by motor back pressure and means for effecting opposite movements of said valves by working pressure from the cylinder including a check-valve-controlled supply connection for each valve, controlled by piston movement and precluding flow towards said cylinder through said connection irrespective of piston position in the cylinder.

12. In a motor, in combination, a cylinder, a piston reciprocable therein, means for continuously venting one end of said cylinder, and means for controlling admission and exhaust with respect to the opposite end of said cylinder including an admission valve opened by the pressure in said last mentioned cylinder end following exhaust valve closure and an exhaust valve whose closing is controlled by motor back pressure, means for effecting opposite movements of said valves by working pressure from the cylinder including a check-valve-controlled supply connection for each valve, controlled by piston movement and precluding flow towards said cylinder through said connection irrespective of piston position in the cylinder, and means for releasing pressure to make the first-mentioned valve movements possible including check-valve-controlled connections one individual to each valve, controlled by piston movement and precluding flow towards its respective valve, and connected with the cylinder bore at points widely separated from the points of communication of said first mentioned connections.

13. In a motor, in combination, a cylinder, a piston therein, admission and exhaust valves to which functionally opposite movements are imparted by compression pressure and motor back pressure respectively, and means for effecting the opposite movements of said valves including a plurality of spaced connections with the cylinder bore for one of said valves, a plurality of spaced connections with the cylinder bore for the other of said valves, and oppositely acting check valves in the connections associated with each valve.

14. In a motor, in combination, a cylinder, a piston reciprocable therein, and valve mechanism for said motor including a valve and controlling means therefor having a pressure area acting to move said valve, and means for supplying pressure to said area and venting pressure therefrom respectively opening into communication with the cylinder bore at points widely spaced longitudinally of the latter and at opposite sides of the midpoint in the normal working stroke and having a common communication with said area, said points so positioned that both are uncovered by one end of the piston on each pass of the latter.

15. In a motor, in combination, a cylinder, a

5 piston reciprocable therein; and valve mechanism for said motor including an admission valve and controlling means therefor having a pressure area acting to move said valve to closed position; and means for supplying pressure to said area and venting pressure therefrom respectively opening into communication with the cylinder bore at points widely spaced longitudinally of the latter and at opposite sides of the 10 midpoint in the normal working stroke and having a common communication with said area, said points so positioned that both are uncovered by one end of the piston on each pass of the latter.

15 16. In a motor, in combination, a cylinder, a piston reciprocable therein, and valve mechanism for said motor including an exhaust valve and controlling means therefor having a pressure area acting to move said valve to open position, and means for supplying pressure to said area and venting pressure therefrom respectively opening into communication with the cylinder bore at points widely spaced longitudinally of the latter and at opposite sides of the midpoint in the normal working stroke and having a common communication with said area, said points so positioned that both are uncovered by one end of the piston on each pass of the latter.

20 25 30 35 40 17. In a motor, in combination, a cylinder, a single acting piston reciprocable therein, and valve mechanism for said motor including a valve and controlling means therefor having a pressure area acting to move said valve, and means for supplying pressure to said area and venting pressure therefrom respectively having check-valve-controlled communication with the cylinder bore at points widely spaced longitudinally of the latter, the first at a point uncovered by the piston near the end of the working stroke of the latter and the second at a point near the opposite end of the cylinder.

45 50 55 18. In a motor, in combination, a cylinder, a single acting piston reciprocable therein, and valve mechanism for said motor including an admission valve and controlling means therefor having a pressure area acting to move said valve to closed position, and means for supplying pressure to said area and venting pressure therefrom respectively having check-valve-controlled communication with the cylinder bore at points widely spaced longitudinally of the latter, the first at a point uncovered by the piston near the end of the working stroke of the latter and the second at a point near the opposite end of the cylinder.

60 65 70 19. In a motor, in combination, a cylinder, a single acting piston reciprocable therein, and valve mechanism for said motor including an exhaust valve and controlling means therefor having a pressure area acting to move said valve to open position, and means for supplying pressure to said area and venting pressure therefrom respectively having check-valve-controlled communication with the cylinder bore at points widely spaced longitudinally of the latter, the first at a point uncovered by the piston near the end of the working stroke of the latter and the second at a point near the opposite end of the cylinder.

75 20. In a motor, in combination, a cylinder having a bore, a piston in said bore, and distribution means, said distribution means including a valve, means for subjecting said valve to a pressure effective upon predetermined reduction

in resistance to effect valve throwing in one direction, and means for throwing said valve in a reverse direction and holding it when therein including means providing an area to be subjected to pressure, and means for subjecting 5 said area to pressure conditions in said cylinder including means providing a plurality of openings into the cylinder at points at which different pressures prevail in different relative positions of the cylinder and piston, and means associated with each of said last mentioned means for limiting flow between the same and the cylinder bore to unidirectional.

21. In a single acting motor, in combination, a cylinder having a bore, a piston in said bore, 15 and fluid distribution means for effecting admission and exhaust relative to the working end of said cylinder including a valve and means for effecting reversals of valve position including oppositely facing areas, means for subjecting one 20 of said areas to a pressure effective to move said valve in one direction when the other of said areas has the pressure vented therefrom, and means for supplying pressure to and venting pressure from said latter area including passage 25 means having communication with the cylinder bore at points widely spaced longitudinally of the cylinder and respectively having controlling valves seating to prevent flow from the cylinder bore and to prevent flow towards the cylinder bore. 30

22. In a single acting motor, in combination, a cylinder having a bore, a piston in said bore, and fluid distribution means for effecting admission and exhaust relative to the working end of said cylinder including a valve and means for effecting reversals of valve position including oppositely facing areas, means for subjecting one 35 of said areas to a pressure effective to move said valve in one direction when the other of said areas has the pressure vented therefrom, and means for supplying pressure to and venting pressure from said latter area including passage means having communication with the cylinder bore at points widely spaced longitudinally of the cylinder, each of said passage means having an end seating controlling valve, the seats for said valves facing, in terms of passage direction, respectively towards and away from the cylinder bore. 40 45

23. In a motor, in combination, a cylinder, a single acting piston reciprocable therein, and valve mechanism for said motor including a valve having controlling means comprising a pressure area acting to move said valve in one direction and means for supplying pressure to said area and venting pressure therefrom respectively, having valve-controlled communications with the cylinder bore at points widely spaced longitudinally of the latter, the first at a point uncovered by the piston near the end of the working stroke 60 of the latter and the second at a point near the opposite end of the cylinder.

24. In a motor, in combination, a cylinder, a single acting piston reciprocable therein, and valve mechanism for said motor including a distributing valve having controlling means comprising a pressure area acting to move said valve in one direction to interrupt admission, and means for supplying pressure to said area and venting pressure therefrom respectively having valve-controlled communications with the cylinder bore at points widely spaced longitudinally of the latter, the first at a point uncovered by the piston near the end of the working stroke 70 75

of the latter and the second at a point near the opposite end of the cylinder.

25. In a motor, in combination, a cylinder having means for venting one end thereof, a piston reciprocable in said cylinder, and valve mechanism for said motor including a valve and controlling means therefor having a pressure area acting when subjected to cylinder working pressure to move said valve, and means for controlling the supply of such pressure to said area and the venting of such pressure therefrom including conduits having their extremities remote from said area opening into communication with the cylinder bore at points widely spaced longitudinally of the latter and at opposite sides of the midpoint in the working stroke and both covered and also uncovered by each end of the piston during each complete cycle of piston movement.

26. A motor of the kind comprising a cylinder vented at one end and having a piston reciprocable therein, and valve mechanism for controlling the movement of the piston including a valve having associated therewith oppositely directed pressure areas adapted to be subjected respectively to pressures acting in opposite directions by which the movements of the valve are controlled, the pressure area directed in one direction being connected by controlled connections respectively with the space within the cylinder towards opposite ends thereof, whereby during the reciprocation of the piston it is alternately subjected to the working pressure in said cylinder and connected to the vented space in the cylinder, characterized in that said pressure area directed in said one direction comprises a single operative surface area which is adapted when subjected through its connection, to the working pressure in said cylinder, to be operated by said pressure to effect a reversal of the valve and is

adapted to permit movement of the valve in its return direction when it communicates through its cylinder connection with the vented portion of the cylinder.

27. In a motor, in combination, a cylinder, a single acting piston reciprocable therein, and valve mechanism for said motor including an admission valve having controlling means including a pressure area for moving said valve to closed position, means for opening said valve when pressure is vented from said area, and means for supplying pressure to said area to close said valve and venting pressure therefrom to permit valve opening including connections having check-valve-controlled communication with the cylinder bore at points widely spaced longitudinally of the latter, the pressure venting means at a point near the beginning of the working stroke of the piston and the pressure supplying means including a communication at a point near the opposite end of the cylinder.

28. In a motor, in combination, a cylinder, a single acting piston reciprocable therein, and valve mechanism for said motor including an exhaust valve having constantly a bias towards closed position and controlling means therefor having a pressure area acting to move said valve to open position, and means for supplying pressure to said area to open said valve and venting pressure therefrom to permit valve closure including connections having check-valve-controlled communication with the cylinder bore at points widely spaced longitudinally of the latter, the pressure venting means at a point near the beginning of the working stroke of the piston and the pressure supplying means including a communication at a point near the opposite end of the cylinder.

WADE H. WINEMAN.

CERTIFICATE OF CORRECTION.

Patent No. 2,103,964.

December 28, 1937.

WADE H. WINEMAN.

It is hereby certified that error appears in the printed specification of the above numbered patent requiring correction as follows: Page 5, first column, line 67, claim 19, for "a" first occurrence, read at; and that the said Letters Patent should be read with this correction therein that the same may conform to the record of the case in the Patent Office.

Signed and sealed this 1st day of March, A. D. 1938.

(Seal)

Henry Van Arsdale,
Acting Commissioner of Patents.
